UNITED STATES PATENT OFFICE.

GIACOMO GALETTI, OF CHICAGO, ILLINOIS.

HOROLOGICAL APPARATUS.

1,160,274.

Specification of Letters Patent. Patented Nov. 16, 1915.

Application filed September 26, 1914. Serial No. 863,663.

To all whom it may concern:

Be it known that I, GIACOMO GALETTI, a citizen of the United States, and a resident of the city of Chicago, county of Cook, and State of Illinois, have invented certain new and useful Improvements in Horological Apparatus, of which the following is a specification.

My invention relates to horological apparatus and more specifically to a device through the medium of which the time of any place upon the surface of the globe of known longitude may be determined with ease and expedition.

15 A further object is the production of an apparatus as mentioned which will be of simple construction and efficient in use.

Other objects will appear hereinafter.

The invention consists in the combinations and arrangements of parts hereinafter described and claimed.

The invention will be best understood by reference to the accompanying drawings forming a part of this specification, and in

25 which—

Figure 1 is a front elevation of a device embodying my invention, Fig. 2 is a top plan view thereof, Fig. 3 is an enlarged detail section taken on substantially line $w-w$ of Fig. 2, the parts of the construction disclosed with the exception of the curtains, being shown in elevation, Fig. 4 is an enlarged detail section taken on line $x-x$ of Fig. 3, Fig. 5 is a section taken on line $y-y$ of Fig. 4, and Fig. 6 is a vertical section taken on line $z-z$ of Fig. 2.

The preferred form of construction as illustrated in the drawings comprises a supporting frame consisting of a plurality of spaced posts or uprights 1 secured at their lower ends in suitable bases 2. The upper and lower ends of posts 1 are rigidly connected by horizontally extending frame members 3. Provided upon the posts 1 between the frame members 3 are outwardly projecting supporting arms 4 each of which, as clearly shown in Figs. 3 and 6, comprises an outer section 4' and an inner section 4'' which telescopes with the section 4' so as to permit of longitudinal adjustment as will be readily understood. The section 4' is secured to the post 1 by means of a set screw 5 and the section 4'' is secured in positions of longitudinal adjustment relative to section 4' by means of a set screw 6. The arms

4 except at the terminal posts 1 project in both directions, that is said arms are arranged in pairs one of which projects forwardly and the other rearwardly from the corresponding post. The sections 4' of the arms of each pair are formed integral as clearly shown in Fig. 6, rendering it possible to use but a single set screw in connection with each pair of said arms for fastening the same to the corresponding post 1. 65

At the outer ends of arms 4 are mounted two sets of rollers 7 and 8, the rollers 7 being of the upper set of rollers and the rollers 8 the lower set. Mounted for travel around said sets of rollers 7 and 8 are endless curtains or belts 9 and 10 respectively held in position by means of studs 11 provided at the respective ends of said rollers which are adapted to engage with perforations 12 provided adjacent the longitudinal edges of said curtains. This provision also prevents slipping of the curtains upon said rollers as will be readily understood. 70

The rollers 7 and 8 at the respective ends 80 of the supporting frame are formed integral and a ratchet wheel 13 is provided at the point of connection of said rollers for effecting rotation thereof. Said ratchet wheel co-operates with a spring pressed pawl 14 85 carried by a manually operable oscillatory lever 15 whereby through oscillatory actuation of said lever the ratchet wheel co-operating therewith will be intermittently rotated to effect corresponding feeding or movement 90 of the belts 9 and 10. A lever 15 and co-operating pawl and ratchet wheel 13 are provided at each end of the supporting frame so that feeding of the belts 9 and 10 may be effected from a position at either end of the 95 device.

Provided at the adjacent longitudinal edges of the curtains 9 and 10, at the front side of the device is an elongated strip 16 rigidly supported by means of supporting arms 17, the strip 16 being so arranged that, during travel of the curtains 9 and 10, the inner longitudinal edges thereof will move in close proximity with the longitudinal edges of said strip. 105

Provided upon the outer sides of curtains 9 and 10 are spaced vertically extending lines 18 indicative of the geographical degrees of longitude, the space between the adjacent lines corresponding to fifteen degrees 110.

longitude as indicated by the graduations coöperating with said lines as clearly shown in Fig. 1. One of said lines 18 is designated the zero line of longitude, the lines at either side thereof being numbered correspondingly so that the endmost lines correspond with 180 degrees east and west longitude respectively. A distance of fifteen degrees of longitude corresponds as is known with a difference of one hour in time. The front side of strip 16 is provided with graduations adapted to register with the lines 18, the graduations upon said strip being numbered consecutively from twelve to twelve to indicate twelve o'clock midnight to twelve o'clock noon, a succeeding numbering from twelve to twelve of said graduations indicating the time from twelve o'clock noon to twelve o'clock midnight again. The hours indicated are further designated A. M.—night referring to the hours from twelve o'clock midnight to six o'clock in the morning; A. M.—day referring to the hours from six o'clock in the morning to twelve o'clock noon; P. M.—day referring to the time from twelve o'clock noon to six o'clock evening; P. M.—night referring to the time from six o'clock in the evening to twelve o'clock midnight, and the portions of said strip referring to A. M.—night and P. M.—night are darkened to further indicate night or darkness. Also provided upon the outer sides of curtains 9 and 10 are spaced parallel horizontal lines 19 which are indicative of the geographical lines of latitude. Stationary strips 20 provided at the respective ends of the device and rigidly supported by the respective ends of strips 16 are graduated for coöperation with the lines 19. The arrangement is such as will be seen, that the strip 16 is positioned at a location corresponding with the equator, the lines 19 at either side thereof or above and below the same corresponding with the north and south geographical latitudes and being numbered to correspond so that the outermost lines 19 will be numbered 90 degrees corresponding with the north and south poles of the earth.

With the arrangement set forth it will be seen that after the curtains 9 and 10 have been set so that the line of longitude of the place or city in which the operator is located is in registration with the proper hour of day shown upon the strip 16, the time at any other place may be readily and easily found providing the longitude of the place is known, the time of any other place being that indicated by the hour graduation upon strip 16 registering with the longitude line of that place. The curtains 9 and 10 are of such size as to be adapted to accommodate the principal cities of the world which will be printed thereon at points on said curtains corresponding with the latitude and longitude of said cities. This being

so it will be seen that after the curtains 9 and 10 have been set as above set forth the time of any city whose name appears upon said curtains may be ascertained immediately. The provision of the lines of latitude are of course no aid in the ascertainment of time, as above described, said lines serving simply as a means of definitely locating geographically the cities at the same time that the time of said cities is being ascertained. With the arrangement disclosed the first letter of the name of the city is commenced at a point corresponding on the curtains with the latitude of the city so that with this arrangement the latitude of a city will be indicated by the graduation upon the plates 20 opposite the first letter of the city in question. 75 80

In order to further indicate the portion of the earth which is in darkness, elongated plates 21 are provided at the upper end of the device adjacent the upper edge of curtain 9, the plates 21 being fixed to posts 22 which arise from the upper frame member 3. The plates 21 it will be observed are positioned to correspond with the portions of strip 16 which correspond with night and slidably mounted upon the ends of members 21 are tubular extensions 23 which afford means of extending or contracting the members 21 in order to correspond with the lengthening and shortening of the days and nights during the different seasons of the year. The front sides of members 21 and extension members 23 thereof are darkened and preferably provided with stars to indicate night. 90 95 100

The outer surface of each of the curtains 9 and 10 is provided with two identical sets of graduations as described above, each set 105 extending one-half way around the curtain or occupying one-half the length thereof so that where one set ends the other commences. The rollers 7 and 8 engaging against the front stretch of the curtains are arranged in 110 convex formation, so that the corresponding front stretch of each curtain which is bulged to correspond, will present exactly one-half of its length between the inner edges of plates 20, the other half of each curtain extending outwardly from said plate edges around the terminal rollers and along the back stretch of the curtain. Thus, through the convex formation of the front portions of the curtains, one-half of the latter will 120 always be exposed between the plates 20, so that as a line corresponding with a particular degree of longitude disappears at the right hand end of the device, a corresponding line of longitude will appear at the left 125 hand end of the device. Through the telescoping connection between sections 4' and 4'' of each of the supporting arms for the rollers 7 and 8, adjustment of the latter is permitted to properly position the same for 130

engagement with the curtains in assembling the device.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the class described comprising a frame; rollers supported by said frame; an endless curtain mounted for travel about said rollers, said rollers being arranged to bulge said curtain at one side of said frame; markings on said curtain indicative of the geographical degrees of longitude; and stationary markings indicative of the hours of a day arranged for coöperation with said first mentioned markings, substantially as described.

2. A device of the class described comprising a frame; a plurality of rollers adjustably supported by said frame; a curtain mounted for travel about said rollers; markings on said curtain indicative of the geographical degrees of longitude; and stationary markings indicative of the hours of a day arranged for coöperation with said first mentioned markings, substantially as described.

3. A device of the class described comprising a pair of parallel movably mounted curtains having markings thereon indicative of the geographical degrees of longitude; and stationary graduations indicative of the hours of a day arranged between said curtains for coöperation with said first mentioned markings, substantially as described.

4. A device of the class described comprising a pair of parallel movably mounted curtains having markings thereon indicative of the geographical degrees of north and south latitude and east and west longitude; and stationary markings indicative of the hours of a day arranged between said curtains for coöperation with said longitude markings, substantially as described.

5. A device of the class described comprising a movably mounted endless curtain; spaced horizontally extending lines on said curtain indicative of geographical degrees of latitude; spaced vertically extending lines on said curtain indicative of geographical degrees of longitude; and stationary graduations indicative of the hours of a day arranged for coöperation with said before

mentioned markings, substantially as described.

6. A device of the class described comprising a pair of movably mounted endless curtains arranged one above the other and parallel with each other; spaced horizontally extending lines on the upper one of said curtains indicative of geographical lines of north latitude; spaced horizontally extending lines on the lower one of said curtains indicative of geographical lines of south latitude; spaced vertically extending lines on said curtains indicative of geographical lines of east and west longitude; and stationary markings indicative of the hours of a day arranged between said curtains for coöperation with said before mentioned markings, substantially as described.

7. A device of the class described comprising a frame; two superposed sets of spaced rollers having parallel vertical axes supported by said frame; a pair of endless curtains movably mounted on said rollers; means coöperating with the endmost of said rollers for manually moving said curtains; markings on said curtains indicative of geographical lines of latitude and longitude; and stationary graduations indicative of the hours of a day arranged for coöperation with said longitude markings, substantially as described.

8. A device of the class described comprising a frame; two superposed sets of spaced rollers having parallel vertical axes supported by said frame; a pair of endless curtains movably mounted upon said rollers, the endmost of the rollers of said sets being operatively connected; means coöperating with said endmost rollers for manually moving said curtains; markings on said curtains indicative of geographical degrees of latitude and longitude; and stationary graduations indicative of the hours of a day arranged for coöperation with said longitude markings, substantially as described.

9. A device of the class described comprising a movable curtain having markings thereon indicative of the geographical degrees of longitude; stationary graduations indicative of the hours of a day arranged for coöperation with said first mentioned markings; and longitudinally adjustable night-indicating members also arranged for coöperation with said longitude markings, substantially as described.

In testimony whereof I have signed my name to this specification in the presence of two subscribing witnesses.

GLACOMO GALETTI.
